OVERHEAD DOOR

Roscoe Fowler, Los Angeles, and Earl F. Murphy,
Inglewood, Calif.; said Murphy assignor to said
Fowler

Application January 14, 1946, Serial No. 641,110

11 Claims. (Cl. 20—16)

1

Our invention relates to a closure structure, particularly as applied to overhead doors, for garages, and the like.

One of the principal objects of this invention is to provide a closure structure of this class in the form of an overhead door, which requires very little or extremely low overhead clearance over the normally closed position of the door, so that no material part of the door moves above, or appreciably above, the horizontal open position of the door.

Another important object of this invention is to provide novel arm and lever means to bring about such movement of the door, or other closure member, from a closed to an open position, or vice versa, and particularly an arm and lever construction in which a cantilever arm causing the swinging of the door or closure member is controlled in its movement by a master arm supporting the door or closure member.

An important object also of this invention is the elimination of tracks, or similar extended means, for guiding the door or closure member in such movement.

A further important object of this invention is to provide a mechanism of this class which requires substantially only a single connection or attachment to the opposite sides of the sides of side members of the frame or jamb of the closure member.

A still further important object of this invention is to provide arm and lever means for a structure of this class in which certain members are readily extensible or contractable to accommodate doors or closures of various lengths or heights.

Still another important object of this invention is to provide a novel booster bracket or lateral extension of the master closure supporting arm to facilitate opening of the closure.

With these and other objects in view, as will appear hereinafter, we have devised an overhead door or closure structure having certain novel features of construction, combination, and arrangement of parts and portions, as will be hereinafter described in detail and particularly set forth in the appended claims, reference being had to the accompanying drawings and to the characters of reference thereon, which form a part of this application, in which:

Fig. 1 is a sectional elevation through a door and frame or jamb therefor, showing our arm and lever mechanism at one side thereof, for supporting and holding the door in a closed position;

Fig. 2 is a similar view thereof through the door and frame, but showing the former in an open position, and showing by dotted lines various positions of the upper portion of the door when moved from the vertical to the horizontal position, or vice versa;

2

Fig. 3 is a fragmentary elevational view taken from the inside of the door, as indicated by 3—3 of Fig. 1.

Fig. 4 is an enlarged transverse sectional view thereof, taken through 4—4 of Fig. 1; and,

Fig. 5 is an enlarged transverse sectional view thereof, taken through 5—5 of Fig. 1, showing one form of extensible construction of one of the door supporting arms.

The door or closure member, designated 1, is of conventional construction and may be of any desired size. It is arranged to be closed over the opening 2^a of the frame or jamb 2. As shown, the frame has only a stop 2^b at the upper portion of the opening to limit the outward or closed position of the upper end of the door or closure member.

At each side of the frame is mounted a duplicate arm and lever mechanism, shown best in Figs. 1 and 2. Since the mechanisms are duplicates, only one will be described.

The whole mechanism is supported on the inner side of a side member 2^c of the frame by a bracket 11, which extends inwardly from such side member. On the inner and lower portion of the bracket is pivotally mounted the master arm 12, such mounting being preferably at the median portion of the arm. One end of the arm, which is the normally lower end when the door is closed, is pivotally connected to the door 1 near the lateral edge. Such pivotal connection is preferably made with a side rail 13, which is secured to the inner side of the door.

On the outer side and upper portion of the bracket 11 is pivotally mounted one end of a positioning lever 14, which, when the door is closed, extends downwardly from its pivotal mounting on the bracket. The normally lower end of this positioning lever is pivotally connected to a cantilever arm 15, the principal function of which is the swinging of the door about its hinge or pivotal mounting on the master arm. The normally lower end of the cantilever arm is pivotally connected to a bracket 16 extending inwardly from the door, near the normally lower end thereof.

In order to swing the positioning lever 14 to effect the movement of the door about its pivotal support on the master arm in the desired manner, the median portion of the positioning lever 14 is connected by a link 17 to a laterally extended lug 12^a on the master arm 12, the axis of the pivotal connection of this lug being positioned between the pivotal connection of the master arm to the door and the pivotal mounting of the master arm on the bracket, but near the latter, this pivotal axis being also positioned at the normally inner side of the master arm, as shown in Fig. 1.

In order to facilitate the shifting of the door 60 from the closed to the open position, and vice

versa, a coil spring 18 connects the other, or normally upper end of the master arm 12, to the inner side of the lower portion of the side member 2^c of the frame, as shown in Fig. 1. The connection of the upper end of the spring to the master arm is off-set inwardly from the line extending between the pivotal connections of the arm with the door and with the bracket 11. This offset is made by a booster bracket 19, which is adjustably connected to said normally other or upper end of the master arm.

In order to prevent the coil spring 18 from interfering with or whipping against the connected ends of the positioning lever 14 and the cantilever arm 15, a shoe 20 is provided for holding the intermediate portion of the spring therefrom. This shoe may be carried by the free end of the positioning lever 14.

In order to apply our arm and lever mechanism to closures of various lengths or heights, we have provided longitudinally adjustable master and cantilever arms. The adjustable portions of these arms may be referred to as telescoping portions. In this instance, the master arm 12 consists of a large central section 12^b and smaller end sections 12^c and 12^d, all of which may be structural channels. The channels 12^c and 12^d are shown positioned within and are longitudinally slidable within the center section 12^b. The center section is slotted, as shown, and the two end sections are connected to the center section by suitable means such as bolts 12^e, which extend through the slots.

In a similar manner, the cantilever arm 15 has interpositioned and longitudinally slidable channels 15^a and 15^b, which are adjustably connected through slots by bolts 15^c.

Though we have shown and described a particular construction, combination, and arrangement of parts and portions, we do not wish to be limited to the same, but desire to include in the scope of our invention the construction, combination, and arrangement substantially as set forth in the appended claims.

We claim:

1. In an overhead door construction, the combination with a frame and a closure member, of a master arm pivotally mounted on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, and a link connecting the intermediate portion of the positioning lever to the master arm between the connections thereof with the closure member and the mounting on the frame and near the latter mounting.

2. In an overhead door construction, the combination with a frame and a closure member, of a bracket secured to the side and intermediate the ends of the frame and extending inwardly therefrom, a master arm pivotally mounted on the inner end of the lower portion of the bracket and pivotally connected at one end to the normally inner side and median portion of the closure member, a cantilever arm pivotally connected at one end to the normally inner side of the normally lower portion of the closure member, a positioning lever pivotally mounted

at one end at the inner and upper portion of the bracket and pivotally connected at its other end with the other end of the cantilever arm, and means operatively connecting the intermediate portion of the positioning lever to the master arm between the connections thereof with the closure member and the mounting on the bracket and near the latter mounting.

3. In an overhead door construction, the combination with a frame and a closure member, of a bracket secured to the side and intermediate the ends of the frame and extending inwardly therefrom, a master arm pivotally mounted intermediate its ends on the inner end of the lower portion of the bracket and pivotally connected at one end to the normally inner side and median portion of the closure member, a cantilever arm pivotally connected at one end to the normally inner side of the normally lower portion of the closure member, a positioning lever pivotally mounted at one end at the inner and upper portion of the bracket and pivotally connected at its other end with the other end of the cantilever arm, means operatively connecting the intermediate portion of the positioning lever to the master arm between the connections thereof with the closure member and the mounting on the bracket and near the latter mounting, and means at the other end of the master arm for counter-balancing the closure member about the pivotal mounting on the bracket.

4. In an overhead door construction, the combination with a frame and a closure member, of a bracket secured to the side and intermediate the ends of the frame and extending inwardly therefrom, a master arm pivotally mounted intermediate its ends on the inner end of the lower portion of the bracket and pivotally connected at one end to the normally inner side and median portion of the closure member, a cantilever arm pivotally connected at one end to the normally inner side of the normally lower portion of the closure member, a positioning lever pivotally mounted at one end of the inner and upper portion of the bracket and pivotally connected at its other end with the other end of the cantilever arm, means operatively connecting the intermediate portion of the positioning lever to the master arm between the connections thereof with the closure member and the mounting on the bracket and near the latter mounting, and a tension spring connecting the opposite end of the master arm to the lower end of the frame.

5. In an overhead door construction, the combination with a frame and a closure member, of a longitudinally adjustable master arm pivotally mounted on the side and intermediate the ends of the frame and pivotally connected at one end to the normally inner side and median portion of the closure member, a longitudinally adjustable cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, and means operatively connecting the intermediate portion of the positioning lever to the master arm between the connections thereof with the closure member and the mounting on the frame and near the latter mounting.

6. In an overhead door construction, the combination with a frame and a closure member, of a master arm pivotally mounted intermediate its

ends on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, means operatively connecting the intermediate portion of the positioning lever to the master arm between the connections thereof with the closure member and the mounting on the frame and near the latter mounting, the opposite end of the master arm having an offset portion extending, when the structure is in a closed position, inwardly from the line pivotally connecting the master arm with the frame and closure member, and a tension spring connecting the inner end of the offset portion with the lower end of the frame.

7. In an overhead door construction, the combination with a frame and a closure member, of a master arm pivotally mounted intermediate its ends on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, means operatively connecting the intermediate portion of the positioning lever to the master arm between the connections thereof with the closure member and the mounting on the frame and near the latter mounting, and a tension spring connecting the opposite end of the master arm to the lower end of the frame, there being provided near the pivotal connection of the positioning lever and cantilever arm a shoe, for spacing the intermediate portion of the spring inwardly when the structure is in a closed position.

8. In an overhead door construction, the combination with a frame and a closure member, of a master arm pivotally mounted intermediate its ends on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, means operatively connecting the intermediate portion of the positioning lever to the master arm between the connections thereof with the closure member and the mounting on the frame and near the latter mounting, the opposite end of the master arm having an offset portion extending, when the structure is in a closed position, inwardly from the line pivotally connecting the master arm with the frame and closure member, and a tension spring connecting the inner end of the offset portion with the lower end of the frame, there being provided near the pivotal connection of the positioning lever and cantilever arm a shoe, for spacing the intermediate portion

of the spring inwardly when the structure is in a closed position.

9. In an overhead door construction, the combination with a frame and a closure member, of a master arm pivotally mounted on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, and means operatively connecting the intermediate portion of the positioning lever to the master arm between the connections thereof with the closure member and the mounting on the frame and near the latter mounting.

10. In an overhead door construction, the combination with a frame and a closure member, of a master arm pivotally mounted intermediate its ends on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, means operatively connecting the intermediate portion of the positioning lever to the master arm between the connections thereof with the closure member and the mounting on the frame and near the latter mounting, and means at the other end of the master arm for counterbalancing the closure member about the pivotal mounting on the frame.

11. In an overhead door construction, the combination with a frame and a closure member, of a master arm pivotally mounted intermediate its ends on the side and intermediate the ends of the frame and pivotally connected at one end to the normally inner side and median portion of the closure member, a cantilever arm pivotally connected at one end to the normally inner side of the normally lower portion of the closure member, a positioning lever pivotally mounted at one end on the frame above the pivotal mounting of the master arm and pivotally connected at its other end with the other end of the cantilever arm, means operatively connecting the intermediate portion of the positioning lever to the master arm between the connections thereof with the closure member and the mounting on the frame and near the latter mounting, and a tension spring connecting the opposite end of the master arm to the lower end of the frame.
